United States Patent

Des. 238,789

Patented Feb. 10, 1976

238,789

AMPLIFIER HOUSING

Charles A. Ross, Fort Scott, Kans., assignor to Road Electronics, Inc., Fort Scott, Kans.

Filed Dec. 16, 1974, Ser. No. 532,955

Term of patent 14 years

Int. Cl. D14—03

U.S. Cl. D26—14 G

Fig. 1.

Fig. 2.

FIG. 1 is a front perspective view of an amplifier housing showing my new design; and

FIG. 2 is an enlarged fragmentary cross-section taken on line 2—2 of FIG. 1.

The undisclosed side and rear portions of the amplifier housing are plain and unornamented.

I claim:

The ornamental design for an amplifier housing, as shown and described.
